DESIGN FOR A RUG.

SPECIFICATION forming part of Design No. 35,588, dated January 14, 1902.

Application filed December 17, 1901. Serial No. 86,314. Term of patent 3½ years.

To all whom it may concern:

Be it known that I, ADOLPH PETZOLD, a citizen of the United States, residing at Philadelphia, Pennsylvania, have invented and produced a certain new and original Design for a Rug, of which the following is a full, clear, and exact description, reference being had to the accompanying drawing, forming a part of this specification.

10 My invention relates to the surface ornamentation of woven rugs; and it consists of the design therefor shown in said drawings. In its essentials it consists of opposite connected curved figures *a*, giving a border-like 15 appearance, one row of these figures being of

less length than the other, and in the space left open thereby is a bunch *b* of roses, flowers, and leaves dependent and extending down into the field center.

I claim—

20 The design for a rug substantially as shown and described.

In testimony whereof I have hereunto affixed my signature this 4th day of December, A. D. 1901.

ADOLPH PETZOLD.
